UNITED STATES PATENT OFFICE

CHARLES E. CATHER, OF WORCESTER, MASSACHUSETTS, ASSIGNOR TO UNITED STATES
ENVELOPE COMPANY, OF SPRINGFIELD, MASSACHUSETTS, A CORPORATION OF
MAINE

TWO-COMPARTMENT ENVELOPE

Application filed August 2, 1926. Serial No. 126,590.

The present invention relates to envelopes for mailing purposes, and more particularly to envelopes which provide two separate compartments in a unitary one-piece-blank structure,—the purpose being to provide a double or duplex envelope for the transmission by mail to the same address of two different classes of postal matter, mailable at different rates of postage.

10 The invention contemplates an envelope structure providing a compartment or pocket of large size to receive bulky matter, such as merchandise, catalogues and the like, which are mailable at a low postal rate, and integral therewith, and within the area of said large compartment, a smaller compartment or pocket, capable of being separately and securely sealed, and adapted to contain the invoice, bill, letter or the like, which, though mailable at a higher postal rate, it is desired to transmit with the bulky matter, under one and the same address. According to the invention, such a two compartment envelope structure is made from a single sheet or blank, and the manufacture is under such simple requirements for gumming, folding and sealing as to render quantity production entirely feasible by the automatic machines which are employed in the manufacture of ordinary single-pocket or standard envelopes. The above and other advantageous features of the invention will be set forth more fully hereinafter, reference being had to the accompanying drawings, in which—

Fig. 1 is a plan view of the sheet or blank from which the envelope of my invention is made.

Fig. 2 is a similar view, illustrating said blank after it has been initially folded.

Fig. 3 is a view illustrating the duplex or two compartment envelope made from the blank of Fig. 1, and showing the two compartments ready for the insertion of their respective inclosures.

Fig. 4 is a view illustrating the envelope with the entrances to the two compartments closed by their respective flaps, and an expedient employed for postal inspection.

53. Fig. 5 is a plan view of the blank used in a modified form of the invention.

Fig. 6 illustrates the envelope made from the blank of Fig. 5.

Like reference characters refer to like parts in the different figures.

Referring first to Fig. 1, the envelope blank provides a rectangular body portion 1, constituting when the blank is folded, the unseamed face or, as it is sometimes called, the front wall of the envelope. On opposite sides of the body portion 1, the blank is provided with side flaps 2 and 3, which, when folded toward each other along the lines 4 and 5, respectively, will overlap substantially at the center of the body portion 1, thus forming the back wall of the envelope by their adhesion longitudinally at the place of overlapping, such adhesion being effected by gumming 6, here shown as extending along the edge of side flap 2, but it could as well be provided along the edge of side flap 3, on the reverse side thereof.

Between the front unseamed wall formed by body portion 1 and the back seamed wall, formed by side flaps 2 and 3, the envelope provides an integral partition 7, in the form of a flap extending from one end of body portion 1 and adapted to be folded along the line 8. This partition 7, in the completed envelope, forms the dividing wall between the two compartments, as hereinafter described, and in the manufacture of said envelope from the blank shown in Fig. 1, the first step in the folding, before the back wall is formed, is to fold this flap 7 over onto the

is formed, is to fold this flap 7 over onto the inner face of body portion 1, as shown in Fig. 2. Thereafter the flaps 2 and 3 are folded over, with the former overlapping the latter, so that the moist gum 6 will adhere to flap 3 and form the center seam of the back wall of the envelope, as shown in Fig. 3. This provides an envelope having two compartments, one a large compartment between the body portion 1 and flap or partition 7, to which access is had for the insertion of mail matter by way of end entrance 9, Fig. 3, and the other a small compartment between side flap 3 and partition 7, to which access is had for the insertion of mail matter by way of an entrance slit 10, formed in the flap 3 a sufficient

distance from its free edge so as to escape being overlapped by the flap 2.

The end entrance 9 to the large compartment is adapted to be closed, after insertion of mail matter, by a flap 11, provided for this purpose either with a metallic fastener of the well known type, as shown in Fig. 6, or with a suitable margin of adhesive 14, as shown in Fig. 3, adapted to be moistened by the user and stuck down against the back wall of the envelope. The entrance slit 10 of the small compartment is adapted to be closed, after the insertion of the mail matter, by a seal flap 12, which in this instance is constituted by an integral extension of the side flap 2, and is provided with a margin of adhesive 13 adapted to be moistened by the user and stuck down against the back wall of the envelope, as indicated in Fig. 4. As shown in Fig. 3, the inclosure for the small compartment is of such size, or is so folded, as to project, along its edge, slightly through the entrance slit 10, thus preventing endwise movement of said inclosure within said small compartment, after the flap 12 has been sealed down.

The envelope structure thus achieved affords complete segregation between the two compartments, so that matter mailable at a low postal or merchandise rate, may be placed in the large compartment, and matter mailable at a higher postal or letter rate, may be placed in the small compartment,—a single address being sufficient for both classes of mail matter. Although both compartments may ostensibly be sealed, the smaller one by the gumming 13 on seal flap 12, and the larger one by gumming 14 on flap 11, nevertheless the construction is such that the lower postal rates on mail matter not inaccessibly sealed may be invoked for the contents of both pockets or compartments, for the reason that the flap or partition 7 is free at all times, in the construction illustrated in Figs. 1 to 4 inclusive, to be pulled out from between the front and back walls of the envelope, as shown in Fig. 4, thus to permit inspection of the contents of either or both pockets without disturbing the seals 13 and 14 of either of them. Moreover, in a variation of the construction which makes a more secure envelope, by the use of marginal gumming 15 and 16 on the flaps 2 and 3, respectively, for adhesion to the partition 7, as shown in Figs. 5 and 6, the same advantage of lower postal rates is obtained, notwithstanding this obstacle against withdrawal or pulling out of the partition 7. The only change made necessary is to replace the sealing gum 14 on flap 11 with a metallic fastener 18, as shown in Fig. 6, and when this is done, the opening of said flap gives access not only to the contents of the large compartment, but also to the contents of the sealed smaller compartment,—this last through the opening 17 between the

partition 7 and the side flap 3. As shown in Fig. 5, said partition 7 need not correspond in size to the body portion 1, but may, if desired, be of lesser width, to correspond substantially to the width of the smaller compartment.

I claim:

1. As a new article of manufacture, an envelope made from a single sheet or blank and providing two compartments, said blank consisting of a rectangular body portion, with a flap projecting therefrom and adapted to be folded upon said body portion, said flap and body portion thereby constituting the opposite walls of the larger of said two compartments, and said blank further providing oppositely located flaps adapted, when folded, to overlap each other and to overlie the first mentioned flap, one of said two last mentioned flaps having a slit constituting the entrance to the smaller compartment of the envelope formed between said flap and the underlying first mentioned flap, and the other of said two last mentioned flaps providing a sealing closure for said slit.

2. As a new article of manufacture, an envelope made from a single sheet or blank and providing two compartments, said blank consisting of a rectangular body portion, with a flap projecting therefrom and adapted to be folded upon said body portion, said flap and body portion thereby constituting the opposite walls of the larger of said two compartments, and said blank further providing oppositely located flaps adapted, when folded, to overlap each other in overlying relation to said first mentioned flap, said overlapping flaps being adhesively secured along their longitudinal edges, and one of them having a slit which forms the entrance to the smaller compartment between said slotted flap and the underlying first mentioned flap, the latter being free to be drawn outwardly from its folded position underlying said overlapping flaps, thereby to permit postal inspection of the contents of both the large and the small compartments.

Dated this 27th day of July 1926.

CHARLES E. CATHER.
